UNITED STATES PATENT OFFICE.

WILLIAM HENRY PAINE, OF SKOWHEGAN, MAINE, ASSIGNOR OF ONE HALF
TO GEORGE CUSHING, OF SAME PLACE.

MACHINE FOR PRINTING OIL-CLOTH IN COLORS.

SPECIFICATION forming part of Letters Patent No. 417,199, dated December 10, 1889.

Application filed June 27, 1889. Serial No. 315,749. (No model.)

To all whom it may concern:

Be it known that I, WILLIAM HENRY PAINE, a citizen of the United States of America, residing at Skowhegan, in the county of Somerset and State of Maine, have invented certain new and useful Improvements in Machines for Printing Oil-Cloth and other Fabrics in Colors; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to certain new and useful improvements in machines for stamping or printing oil or floor cloth and other analogous goods in colors.

The object of my invention is to provide an apparatus or machine which, being driven by power, will take the fabric to be printed upon and convey it beneath the printing or stamping rollers, the fabric being carried by an endless revoluble table mounted upon rollers; and my invention consists in the construction and combination of the parts, as will be hereinafter fully set forth, and particularly pointed out in the claims.

In the accompanying drawings, which illustrate my invention, Figure 1 is a side view, the major part thereof being in section. Fig. 2 is a plan view. Fig. 3 is a sectional view 35 taken through the line $y-y$ of Fig. 2. Fig. 4 is a longitudinal section of one of the printing-rollers. Fig. 5 is an end view of one of the printing-rollers, showing the means for operating the same and conveying the ink or paint from the wells to the surface of the rollers. Fig. 6 is a detail view illustrating the construction of the slats forming the endless table.

A refers to the frame of the apparatus, which is mounted upon rollers $a-a$, said frame consisting of vertical standards and horizontal beams, which serve as a support for the transverse shaft of the apparatus, the transverse beams also supporting a table A' . Above the table are secured guides or tracks

B, the ends of which are curved downwardly, as shown at B' . Above these tracks is secured an endless belt C, made up of a series of rollers and hinges of proper construction having pins which pass through the hinged plates for holding the rollers together. Two of these endless belts of rollers are employed, each endless belt passing over tracks supported upon the longitudinal beams b .

At each end of the frame-work of the machine and upon the central longitudinal beams thereof are journaled shafts, which carry octagonal pulleys D D, the shaft D' having journaled thereon a tapering pulley D^2 , over which a belt is passed, said belt passing over a tapered pulley E, journaled upon a shaft near the center of the frame-work. This shaft also carries a loose pulley and a pulley for applying power thereto.

F refers to an endless belt made up of a series of transverse slats suitably hinged together, these slats being placed over the octagonal pulleys D D and moved in the direction indicated by the arrow when the pulleys are rotated. These transverse slats F are 75 provided on their upper surfaces with projecting pins $f-f$, and also with grooves or recesses f' , within which will lie, so as to move partly therein, the lower portions of the cog-wheels attached to the printing-rollers. The 80 under sides of these slats F at their central portions are also provided with pins f^2 , which enter a groove formed in the guide-plate g, attached beneath the upper portion of the slatted endless belt, so that the pins f^2 will 85 enter the grooved guide and hold the belt F from lateral movement, this lateral movement also to a certain extent being prevented by the cog-wheels of the printing-rolls entering the grooves or recesses f' .

Upon the upper side pieces of the frame A, at one end of the machine, is mounted a smoothing-roller H, journaled upon cross-piece h, one end of which is pivotally attached to a short upright, while the other end is adjustably secured in a slotted upright, thereby providing means for adjusting vertically the smoothing-roller, so that its distance above the endless belt F can be varied according to the thickness of the fabric. This presser

roller or cylinder H is preferably covered with felt or other suitable analogous material which will not be injured by the projecting pins or brads in the upper faces of the slats, 5 which enter the fabric and hold the same securely thereon. So as to project in front of this smoothing and pressing roller H are two projecting pieces, to which are secured a transverse bar I, said bar having an opening 10 through which the fabric is passed from the roll containing the unprinted material.

To the rear of the smoothing-roller H, upon the upper side frames of the apparatus, are mounted three printing-rollers K, K', and K², 15 which are journaled upon suitable shafts, and they are geared to each other by any suitable mechanism, so as to rotate in unison. The mechanism for gearing these shafts together may be either a series of cog-wheels 20 mounted in a suitable frame or belts mounted on pulleys attached to the extended ends of the shafts supporting said rollers. The roller shown in Fig. 4 has its inner face adjacent to each end tapered to receive disks having bevelled edges, said disks being connected to each other by rods k k, which are screw-threaded at their ends and provided with nuts for drawing the disks k' toward each other to hold them securely to the rollers. The printing-rollers are provided on their outer surfaces with ordinary stereotype or electrotype plates, such as have been previously employed in the manufacture of oil-cloth for printing and impressing the lines upon the 35 surface thereof. One of the disks k' is provided with a hub and means for securing the same rigidly to the shaft. The cog-wheels L are also keyed or otherwise secured to the shafts of the printing-rollers, while the cog- 40 wheels L' may be loosely mounted thereon, and are provided with segmental slots l, through which passes a bolt l', which connects the end of an arm L² with this slot, said arm being keyed or attached to the shaft of the 45 printing-roller. By means of this construction the printing-rolls can be adjusted to register with each other. The shafts of the printing-rolls near their ends are journaled upon a movable bar M, pivoted at one end to 50 the standard m. A standard m', having a vertical slot through which passes a bolt connected to the bar M, provides a means for adjusting vertically the printing-rolls. The bar M also carries a vertical standard n and a 55 pivoted bar N, within which are journaled shafts, serving as supports for the rollers which move in the ink or paint wells, the wells being suspended beneath the bars M. The shafts upon which are mounted the ink 60 or paint wells are provided with gear-wheels, which mesh with gear-wheels mounted on the shafts of the feed-rollers P, these feed-rollers taking the paint from the paint-rollers and supplying it to the surface of the printing- 65 rolls.

The bar N, which is pivotally attached to

the bar M, is connected by a flexible connection, as a spiral spring, to the rigid standard n, said spring serving to hold the feed-rollers against the printing-rolls to properly feed 70 the paint thereto, and also provides a means for throwing the gear-wheels of the feed-rollers out of mesh with the cog-wheels of the printing-rolls, so that said feed-rollers can be turned by hand to properly mix the paint preparatory to starting the machine, and as the ink and feeding rollers are journaled at different distances from the pivotal point of the bar N by moving said bar greater or less pressure of the feed-roller upon the inking- 75 roller can be attained, as may be desired.

In practice different-colored inks are placed in the ink-wells, so that the printing-rollers will give different impressions in different colors. At the terminal portion of the series 80 of printing-rolls I place what I consider one of the essential features of my invention—viz., a mashing-roller Q. This roller is journaled in an adjustable frame of substantially the same construction as that in which the 85 smoothing-roller H is mounted. This roller is intended to smooth the paint or ink after it has been applied to the oil-cloth. This roller can be either made of metal or other suitable material, and may be provided with means 90 for wiping the same.

The feed-rollers P may be mounted in the bars N upon journals carried by screw-threaded rods, so that the bearings of said rollers can be adjusted to and from the ink-wells, 100 and the slotted bar I may also carry an adjustable piece or follower, which can be moved by turning suitable set-screws to enlarge or diminish said slot.

I have stated that the printing-rollers K, K', 105 and K² can be suitably geared to each other; but in practice I prefer to provide the grooves f', adjacent to the ends of the transverse boards of the endless belt F, with either projecting pins or casting secured within said 110 grooves to form rack-teeth, Fig. 6, with which the cog-wheels L and L' will engage, such construction being illustrated in the accompanying drawings.

The slats which make up the endless belt 115 are hinged to each other, and the leaves of said hinges are slotted, so that when the hinges are properly adjusted they will provide close-fitting joints between the slats when the ends are placed next to each other, thus 120 providing a smooth surface upon which the fabric rests while being printed.

I am aware that prior to my invention it has been proposed to use a series of printing-rolls, feeding-rollers, and ink or paint wells 125 for applying different colors to textile fabric.

In printing oil-cloth with my improved apparatus there may be left a selvage upon each side of the fabric, and when such selvage is left unprinted it is through this part of the 130 fabric that the pins or brads in the endless revolving table F pass.

Having thus described my invention, what I claim as new, and desire to secure by Letters Patent, is—

1. In a device for printing textile fabric, 5 as oil-cloth, the combination of two or more printing-rolls and a revolving table made up of slats hinged to each other, said revolving table having pins for engaging with the fabric to be printed upon, whereby the fabric is carried beneath the printing-rolls and said printing-rolls rotated by the movement of the table, substantially as shown, and for the purpose set forth.

2. In a machine for printing textile fabric 15 in the manufacture of oil-cloth, a frame carrying recessed guideways B', endless belts made up of rollers supported by said guideways, and a revolving table made up of a series of slats which are hinged to each other, said table being supported by the endless chains of 20 rollers, said table having pins and recesses f', into which pass the gear-wheels attached to the printing-rolls, substantially as shown, and for the purpose set forth.

25 3. The combination, in a machine for printing textile fabrics, of a movable table made up of a series of transverse slats hinged to each other, said slats being provided adjacent to their ends with rack-bars, and a series of 30 printing-rolls having gear-wheels adapted to engage with said rack-bars, so as to be rotated in unison therefrom, substantially as shown, and for the purpose set forth.

4. The combination, in a machine for feeding and printing fabric, of an endless belt F, 35 made up of a series of slats, said slats carrying near their ends rack-bars, and printing-rolls mounted in frames above said slats, said printing-rolls being provided with driving-wheels L and L', one of said driving-wheels 40 having a segmental slot l and an arm L² attached to the shaft of the printing-roll and provided with a bolt for connecting the same with a gear-wheel l', thus providing a means 45 for adjusting the printing-rolls, substantially as shown, and for the purpose set forth.

5. The combination, in a printing-machine, of a printing-roll revoluble, as described, a frame for said roll having adjusting means for raising and lowering the same, a bar N, 50 pivoted to said frame, an ink and feed roll supported thereby, a spring for holding the end roll in contact with the printing-roll, and an endless table of slats for moving the material and actuating the several rolls, substantially as set forth.

6. The combination, in a machine for printing textile fabric, of the expansible printing-rolls K, the inner surfaces of the ends thereof being beveled, disks adapted to engage with 60 said beveled ends, rods for drawing said disks toward each other, one of the disks being provided with means for attaching the same rigidly to the shaft of the printing-roll, and driving-wheels L and L', mounted on the 65 ends of the shaft, one of said wheels being rigidly keyed directly to the shaft, while the other is slotted and engages with an arm L², which is capable of being rigidly connected to the shaft, substantially as shown, and for 70 the purpose set forth.

7. The combination, in a machine for printing textile fabric, of a revolving table F, made up of a series of slats, the inner faces of said slats being provided with pins f², 75 which engage with a grooved guideway g, attached beneath the endless belt of slats, and printing-rollers having cog-wheels which engage with rack-bars attached to the outer faces of the slats which make up said endless belt, and means, substantially as shown, for rotating the endless belt, for the purpose set forth.

In testimony whereof I affix my signature in presence of two witnesses.

WILLIAM HENRY PAYNE.
